Primary Examiner — Calvin E Vansant*Assistant Examiner* — Giang Hoang Tran(74) *Attorney, Agent, or Firm* — Knobbe Martens Olson & Bear LLP(57) **CLAIM**

The ornamental design for a vehicle fender, as shown and described.

DESCRIPTION

FIG. 1 is a front, first side, and top isometric view of an embodiment of a vehicle fender embodying the new design; FIG. 2 is a front, second side, and bottom isometric view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

Broken lines are used to illustrate features and/or environmental structures and form no part of the claimed design.

1 Claim, 8 Drawing Sheets(56)
